(57) **CLAIM**

What is claimed is the ornamental design for a microphone cover, as shown and described.

DESCRIPTION

FIG. 1 is a perspective view of the front of a microphone cover;

FIG. 2 is a perspective view of the back of the microphone cover;

FIG. 3 is a front view of the microphone cover;

FIG. 4 is a back view of the microphone cover;

FIG. 5 is a left side view of the microphone cover;

FIG. 6 is a right side view of the microphone cover;

FIG. 7 is a bottom view of the microphone cover;

FIG. 8 is a top view of the microphone cover; and,

FIG. 9 is a contextual perspective view of the microphone cover showing a microphone.

The broken lines in FIGS. 1-9 represent portions of the microphone cover that form no part of the claim.
